MODELING SPATULA

Alberto Merin Barroso, Los Palos, Cuba

Application July 23, 1948, Serial No. 40,272
In Cuba August 13, 1947

3 Claims. (Cl. 219—21)

1

The present invention relates to modelling spatulae in general and more specifically to those employed in dental work.

As is well known, in the modelling of dental work two different types of conditions met with, one in which the modelling instrument must be heated within certain limits and kept at that temperature during relatively long periods of time and the other in which the heating of the tool must of necessity be intermittent. These conditions are governed by two principal facts which are, the nature of the work that is being done and the class of material employed.

From the earliest time the work of the dentist in this field has been hampered by the lack of adequate tools and the efforts to eliminate that inconvenience have led to the production of numerous types of modelling spatulae which, from the operator's viewpoint, can all be classed in two principal groups. The first group includes all spatulae in which the heating element is not contained in the spatula; to this group belong all those that require to be heated over a spirit lamp, gas burner or the like. In the second group are classed all the spatulae in which the heating element is incorporated in the spatula, generally in the blade element; at present this group is composed almost entirely of the so called, electric spatulae which are heated by passing an electrical current through an electrical resistance attached to the blade, the connecting wires passing through the handle of the spatula.

Those of the first group are employed exclusively in cases where the application of heat must be intermittent while, on the other hand, the ones included in the second group are generally used when a continuous application of heat is required for though they can be used in intermittent work they are not well adapted for it. One of the principal defects of all known spatulae is that none of them can be employed as a two purpose instrument, that is, that none of them is equally efficient in both of the types of work mentioned and this lack of adaptability results in great inconvenience to the worker who is obliged to change constantly from one spatula to another.

One of the principal objects of the present invention is to provide a two purpose electrical spatula that can advantageously replace the modelling spatulae and the heating system now employed by the dentist and the prosthesis worker.

Another object of the present invention is to provide an electrical spatula so designed and contrived that it furnishes the operator with a model-

ling instrument which, due to its specific construction and the incorporation of the heating element in the blade, the latter instantly acquires the necessary temperature for performing its work in the most advantageous manner when gutta-percha, wax, paraffin, etc., are employed.

Still another objective is to provide an electrical spatula, the temperature of which can be regulated in accordance with the type of work to be performed and the class of material that is being used.

A further object of the invention is to provide a double purpose spatula which allows the operator to change instantly from one type of work to the other without the necessity of performing any complicated change or losing an instant of time.

An additional object of the invention is to provide a spatula characterized by the fact that the novel details of construction included in the blade, in combination with the electrical circuit employed, permit the operator to not only heat the blade either continuously or intermittently but also to choose the temperature best suited for the work.

Other objects and advantages of my invention will be easily appreciated, by those expert in the art, during the course of this specification with the help of the annexed drawings in which each part is represented by the same reference character in the different views.

In the drawings:

Figure 1 is a top view of the current regulating member which at times can also be employed as a heating member;

Figure 2 is a vertical section along the line 2—2 of Figure 1;

Figure 3 is a perspective view showing the spatula member inserted between the terminals of an electric circuit contained in said current regulating member;

Figure 4 shows a modification of the terminals of Figure 3;

Figure 5 is a lateral view, partly sectional, of the spatula member.

Figure 6 is a top view of the spatula blade, partly broken away and on a larger scale, showing details of the different elements included in the blade.

Figure 7 is a cross sectional view, on a slightly larger scale, of the spatula handle along the line 7—7 of Figure 5; and

Figure 8 is a section, on a larger scale, along the line 8—8 of Figure 6.

In the preferred embodiment of my invention,

illustrated in the drawings, 1 indicates the blade member of the spatula, said member comprising the combination of metallic element 2, which is a good conductor of both heat and electricity, with the included and spaced metallic elements 3 which are poor conductors of electricity. The element 2 may be made from any of the well-known metals which are good conductors of heat and electricity, such as silver, copper, etc. The elements 3 may be made of any suitable metal or alloy which is a poor conductor of electricity, as for example: Nichrome, and other nickel, chromium and nickel-chromium-iron alloys, etc. The elements 3 are contained in the lateral edges of said element 2 and firmly attached in direct electrical contact with it by any suitable means while projecting out slightly from the edges of said element 2, said elements 3 extending forward along the lateral edges of element 2 to points relatively near its end, then curving inwards and then backwards as illustrated in Figure 6 by the broken lines, said elements 3 project backwards from the base of element 2 in order to form the terminal 3' to which electrical conductors 4 are firmly attached, said conductors 4 being preferably of larger diameters than terminal 3', said conductors 4 then extend backwards within the handle of the spatula and are surrounded and completely insulated by refractory material 5 enclosed in casing 6 forming the spatula handle, said casing being closed at the end furthest from the spatula blade by a removable cap 7 provided on its inner face with metallic pins 8 that penetrate tube-like receptacles forming the terminals of conductors 4 to establish an electrical connection between said conductors 4 and conductor wires 9 that extend from said pins 8 to plug 10 furnished with contacts 10' which can be plugged in on any of the different electrical circuits included in the current regulating member.

The current regulating member of the combination comprises a cylindrical casing or shell 11 enclosing electrical transformer 12 which can be connected to any suitable source of electrical energy by conductors 12', said casing 11 having on its upper portion 13 two spaced and projecting elements 14, said elements, which form the metallic terminals of an electric circuit, are insulated from each other and from said casing and are attached to portion 13 of the latter by screws 15, said terminals 14 being connected by leads 16 to the secondary circuit of transformer 12. The other portion of casing 11 presents openings 17 and 17' through which contacts 10' of plug 10 penetrate to establish contact with circuits formed by tapping the secondary winding of the transformer 12, thus permitting the user of the spatula to obtain the current best suited for the work.

From the foregoing it is seen that the invention covers an instrument which comprises the combination of a spatula member, which includes a novel type of heating element, and a current regulating and heat applying member, said combination being so designed that said members are interdependent to such an extent that the principal object of the invention, the production of a double purpose instrument, can not be obtained in the absence of one of said members.

As has already been said, the instrument is equally suitable for work requiring an intermittent application of heat or for the class of work in which the application of heat must be continuous.

In the first case the procedure is as follows: The blade of the spatula is thrust between terminals 14 that project from upper portion 13 of casing 11, said terminals being so spaced that when the blade of the spatula is thrust between them each one of elements 3 lodged in the edges of the spatula and projecting outward from them, is firmly pressed against one of said terminals 14 thus closing the circuit and allowing the current to flow from one of the terminals to the resistance element 3 in contact with it then through metallic element 2 to the other resistance element 3 and from this to the other terminal of the circuit, and due to the resistance offered to the passage of the current by said two elements 3, heat is generated in them and is transmitted by contact to element 2 thus raising its temperature to the required point.

When it is required to maintain the spatula heated continuously the spatula circuit is simply plugged in at whichever of the circuits ending at 17 or 17' furnishes the current best suited for the work thereby establishing a flow of current through one of the wires 9 and a connector 8 to one of the resistance elements 3, across element 2 to the other resistance element 3, then to conductor 8 and wire 9 to the current regulating member.

I have found that in both of the heating processes mentioned the blade of the spatula is raised to the required temperature almost instantly and that the change from one to the other can be made in a few seconds under normal working conditions.

Although the inclusion of the resistance elements in the sides of the spatula blade can be performed in any suitable manner, I have discovered that the best results are obtained when the previously formed resistance elements are set up within a suitable mold and the metal that is to form the blade is poured in a molten condition into said mold or, in other words, when the blade metal is cast on the resistance elements in such a manner that the latter occupy the positions shown in the drawings. This constructional detail is specially noteworthy because it represents a complete departure from all the methods previously employed for attaching the resistance element to the blade of the spatula. Up to the present it has been usual to insert some insulating material like asbestos, porcelain, etc. between the resistance and the blade, so that the current will only circulate through the resistance or stated differently, that the blade element does not form part of the electric circuit. This insulation introduced between the heating element or resistance and the blade of the spatula makes the operation of heating the latter slower and at the same time introduces an element of weakness in the union of said parts. By casting the blade directly on the spaced resistance not only do I obtain a stronger and more permanent union but also establish direct electrical contact between said resistance elements and the blade which thus forms part of the circuit in which the current circulates, something entirely new, and as I have found out by numerous trials and experiments the excellence of the thermal contact so established is such that the blade is heated in a fraction of the time required by the methods usually employed.

Both the foregoing description and the annexed drawings refer only to a particular embodiment of the invention for, as anyone versed in the art can easily see, the combination de-

scribed admits several constructive changes without departing from the spirit of the invention. Thus, for example, instead of using plug 10 and inlet apertures 17 and 17' to connect the spatula blade circuit to the different circuits formed with the leads 18 of the taps in the secondary winding of transformer 12, a suitable switch may be installed on casing 11 for the purpose, thus making the connections of conductors 9 with the current regulating member of the combination permanent.

Having disclosed my invention and given a detailed description of a preferred embodiment, I claim:

1. Improvement in modelling spatula comprising in combination, a metallic blade element substantially enclosing two spaced metallic elements of lower electrical conductivity extending along the lateral edges of said blade element and projecting slightly from said edges, said low electrical conductivity elements being attached at their rear ends to electrical conductors that connect them to a current regulating member which is in turn connected to a source of electrical energy.

2. Improvement in modelling spatula as in claim 1, characterized by the fact that the portions of said metallic elements of low electrical conductivity included in the edges of said metallic blade element are in direct electrical con-

25 tact with said blade element and extend from its base to points situated near its end.

3. Improvement in modelling spatula as in claim 1, characterized by the fact that said current regulating member of the combination comprises a casing, an electric transformer within said casing, electric circuits of different voltages formed by tapping the secondary winding of said transformer, the terminals of said circuits being brought to said casing at points suitable for connecting them by means of conductors passing through the handle of the spatula to the heating circuit in the spatula blade, an additional electric circuit formed with the secondary winding of said transformer, said circuit having insulated and spaced metallic terminals that project out from said casing; and means for connecting the primary circuit of said electric transformer to a source of electrical energy.
